(57) **CLAIM**

The ornamental design for a wall block, as shown and described.

DESCRIPTION

FIG. 1 is a perspective view of a wall block, as viewed from the front, top, and one side of the block.

FIG. 2 is a front elevation view of the wall block of FIG. 1.

FIG. 3 is a rear elevation view of the wall block of FIG. 1.

FIG. 4 is a right side elevation view of the wall block of FIG. 1.

FIG. 5 is a left side elevation view of the wall block of FIG. 1.

FIG. 6 is a top plan view of the wall block of FIG. 1.

FIG. 7 is a bottom plan view of the wall block of FIG. 1; and, FIG. 8 is a perspective view of the wall block of FIG. 1, as viewed from the rear, top, and one side of the block.

The regular broken lines in the drawings represent unclaimed features and form no part of the claimed design.

1 Claim, 5 Drawing Sheets
